UNITED STATES PATENT OFFICE.

ABRAHAM WOOD, OF RAMSBOTTOM, ENGLAND.

GRENADE AND LIKE THROWING APPARATUS.

1,273,301.

Specification of Letters Patent. Patented July 23, 1918.

Application filed March 8, 1917. Serial No. 153,378.

To all whom it may concern:

Be it known that I, ABRAHAM Wood, a subject of the King of Great Britain and Ireland, and resident of Ramsbottom, in the 5 county of Lancaster, England, have invented certain new and useful Improvements in Grenade and like Throwing Apparatus, of which the following is a specification.

This invention refers to and consists of a 10 new or improved construction of portable, pneumatic (compressed air) throwing apparatus, chiefly for use in throwing grenades and the like, as used in warfare.

One of the features of the improved apparatus 15 is an air-holding chamber or accumulator, within which air may be compressed, and also within which is a movable member or members adapted, on being made free and with the air compressed to be operated by the air. Another feature is a 20 throwing arm and grenade or like holder adapted to be operated by the said movable member or members. A further feature of the improved apparatus is an arrangement 25 of devices whereby, on the desired momentum having been given to the grenade, the motion of the throwing arm is suddenly arrested, while the grenade is free to continue its flight. Another feature of the apparatus, 30 in one form, is that the air serves both to produce the movement of the arm for throwing, and to arrest such movement when the grenade is due to leave the holder.

The apparatus preferably takes the form 35 of three light metal tubes arranged in an upright position (or nearly so) upon a suitable stand. Within certain of the tubes are plungers, each provided with a cup-leather or like packing. The tubes communicate 40 with each other, and in conjunction with the plungers, collectively form a storage chamber or accumulator for air, a non-return air-inlet valve being provided to allow of air being pumped into the tubes until a consider- 45 able pressure is obtained. Axially supported in brackets secured to the top ends of two of the tubes is a light wood staff or throwing arm, such arm and the plungers being arranged, or connected with each 50 other, in such manner that, upon the plungers moving up within the tubes, the throwing arm and holder are rapidly moved through a curved path. The throwing arm may normally overlie the top ends of the 55 tubes and have a movement of about a quarter of a revolution about its axis, but it

will preferably normally lie alongside the tubes and have a movement of about half a revolution. In the first named arrangement the plungers will operate directly upon the 60 throwing arm, while in the second named arrangement the plungers will operate the throwing arm through a chain and quadrant or the like. In addition to comprising 65 means for throwing a grenade, the apparatus may also comprise means for automatically "firing" the grenade.

Upon Sheets 1 and 2 of the accompanying drawings, Figures 1 to 9 illustrate the apparatus in the form in which the throwing 70 arm normally lies alongside the tubes, and moves through about half a revolution in throwing the grenade, this being the preferred construction.

Upon Sheet 3, Fig. 10 illustrates the apparatus in the form in which the throwing arm normally overlies the top ends of the tubes and moves through about a quarter of a revolution in throwing the grenade.

The several figures of the drawings may 80 be described as follows: Fig. 1 is a front view, Fig. 2 a side view, and Fig. 3 a plan of the throwing apparatus, the working parts being shown in the ready-for-throwing position.

Fig. 4 is a further side view but showing the working parts in the after-throwing position.

Fig. 5 is a side view of the apparatus when packed up ready for transit.

Fig. 6 is a front sectional elevation of the tubes alone, to a larger scale, while

Fig. 7 is a sectional plan of the tubes on line $\alpha-\alpha$.

Fig. 8 is an enlarged front exterior elevation, and

Fig. 9 an enlarged side sectional elevation of the upper part of the machine.

Fig. 10 is a side elevation of the modified machine.

Fig. 10^a is a sectional plan of the post and tubes shown in Fig. 10.

Fig. 11 is an enlarged vertical section of the lower end of one of the plungers.

Fig. 12 is an enlarged longitudinal section of one example of the grenade holder, when used for throwing only.

Fig. 13 is a longitudinal section of the grenade holder and a side elevation of the throwing arm when used for both "firing" 110 and throwing a grenade.

Fig. 14 is a longitudinal section of a fur-

ther example of holder for both "firing" and throwing a grenade.

Fig. 15 is a longitudinal section of a holder fitted with grenade holding and automatic releasing means.

Fig. 16 is a cross sectional elevation of a trench with the grenade-throwing machine shown in Figs. 1 to 9 in position.

In the preferred construction of apparatus shown in Figs. 1 to 9, a^1, a^2, a^3 are three light tubes, preferably of solid drawn steel. The three tubes are of equal diameter and the two outer tubes a^1, a^3 are of equal length, while the central tube is shorter than the outer tubes. The three tubes are united at their lower ends by, and open into a hollow header or cap b^1 , while they are braced or held together at the upper end of the central tube a^2 by a bracing or yoke-piece b^2 , the upper end of the tube a being also closed by such yoke-piece, see Figs. 6 and 9.

In one with, or secured to the cap b^1 , is a spindle b^3 , see Fig. 6, the projecting ends of which form trunnions by which the tubes are axially supported in bearings formed in the raised and bifurcated forward part of the elongated wood base c , a bearing cap or bar c^1 , on each side, serving to hold the trunnions in the bearings. As shown in Figs. 1 and 3, the base c is comparatively narrow and long, the length, however, being preferably such as not to exceed the width of a trench, see Fig. 16, although, where the machine is not required for use in a trench, the base may be longer.

At their top ends the tubes a^1, a^3 are fitted with the curved brackets d, d which extend rearwardly and upwardly from the tubes. By means of stays e, e pivotally secured at one end to the brackets d, d and detachably connected at the other end by say wing screws or bolts and nuts, to the base c , the tubes are held rigidly in relation to the base. At any suitable point in the tube a^2 or in the cap b^1 , is fitted a non-return air inlet valve, provided with a stem b^4 to which an ordinary hand air pump may be connected.

To the tube a^2 is fitted a pressure gage b^5 , preferably removable, so as to be used for quickly exhausting the tubes when required. Within the tubes a^1, a^3 are plungers f, f each almost equal in length to the tubes.

At their upper ends the plungers are connected to a wood cross-bar f^1 , the connection being made as rigid as possible so as to prevent any sidewise or endwise movements of the two plungers relatively to each other, and also so as to cause the plungers to move as one. At, or near their lower ends, the plungers are each fitted with one or more cup leathers or similar packing f^2 , see Figs. 6 and 11. When two leathers are provided, the leathers are spaced apart by a spacing block f^3 , see Fig. 11. The said brackets

d, d , near their free extremities, carry between them a spindle d^4 . Upon such spindle is loosely mounted the throwing arm g , and also a quadrant h .

The throwing arm is preferably made of wood, such as hickory or lance-wood, and where it fits the spindle it is provided with a metal bush. The quadrant is composed of two curved sheet-metal plates, between which lies a curved (wood) race block, see Fig. 9, the plates and block being firmly secured together by screws, or bolts and nuts. The arm and quadrant may, if desired, be mounted in ball bearings. The throwing arm lies between two further and smaller plates h^1, h^1 , which are secured to the arm by nuts and bolts i, i , while in each of such plates is a slot i^1 through which, and holes in the side plates of the quadrant, a further bolt i^2 passes, this latter, on its nut being slackened, allowing the throwing arm to be adjusted to different angular positions relatively to the quadrant. After tightening the nut of the bolt i^2 , a wood wedge i^3 may be pushed in between the bolt i^2 and the throwing arm, the wedge thereby helping to prevent the parts accidentally altering their relative positions. The said brackets d, d also carry between them a further fixed spindle d^2 and upon such spindle and preferably in ball or roller bearings, is mounted a sprocket wheel j .

Connected at one end, and centrally, to the cross-bar f^1 of the plungers by say a pin f^1 is a chain f^5 , which, after passing below the sprocket wheel j , is secured at its other end to a loop h^2 on the quadrant h .

Clamped to the tubes a^1, a^2, a^3 near their lower ends (Fig. 2) is a bar or lug a^4 , to which is hingedly connected a double-ended or forked hook a^5 , the hook being so formed on its hinge side as to normally assume the position shown in Fig. 4. Upon the throwing arm g is fixed a U-shaped plate g^1 , while passing through the arm and the plate is a long pin g^2 , the ends of which project on each side of the arm. The ends of the pin, when the arm is moved down and toward the tubes a^1, a^2, a^3 , are automatically engaged by the hook a^5 , the nose or face of the hook riding over the ends of the pin and the hook falling behind the ends of the pin as the arm completes its movement, see Fig. 2. In one with, or secured to the hook a^5 is a handle a^6 which preferably inclines away from the tubes, so that its weight may help to hold the hook in engagement with the pin g^2 when the arm is lowered.

Upon the throwing arm, and near its free end, is mounted the device for holding the grenade, or other object requiring to be thrown. Such devices may take various forms, but in the example shown it comprises a plain cylindrical sheet-metal cup h , provided on its underside with a bifur-

cated sheet-metal flange k^1 , the forks of which are adapted to embrace the throwing arm g . A bolt k^2 , passing through the forks of the cup flange and through a hole in the throwing arm, serves to pivotally connect the cup to the arm and thereby enable the cup to take up various angular positions relatively to the arm. In each of the forks of the cup flange k^1 is a segmental slot k^3 , 5 through which, and a hole in the arm, a bolt k^4 passes. Such bolt is provided with a head at one end and a wing-nut at the other end, so that, after setting the cup to the desired angular position, the nut and bolt enable 10 the forked flange and the cup to be firmly clamped to the arm. Within the cup k are two or more strips of thin spring metal k^5 , 15 see Fig. 12, the strips being either integral, or separate and lying at right angles to and crossing each other, and being secured centrally to the cup by a screw k^6 while their extremities extend slightly beyond the top edge of the cup. This arrangement of grenade holder has been found particularly 20 suitable for what are known as "cricket ball" grenades. When a grenade is placed in the cup the arms produced by the spring strips hold it in the cup with a gentle yielding pressure.

30 The working of the machine may now be described. The base c of the machine having been placed with its sides parallel with the intended line or direction of throw, air is pumped into the tubes a^1 , a^2 , a^3 by means 35 say of an ordinary hand pump via the non-return valve, the pumping being continued until a considerable pressure is obtained in the tubes, according to the distance the grenade requires to be thrown. The throwing 40 arm g during the pumping may either be lowered and latched as in Fig. 2 or left raised as in Fig. 4. In this last named case, the pumping need not be carried on for so long as when the arm is lowered in view of 45 the fact that, upon afterward lowering the arm, the pressure is increased by the forcing down of the plungers f , f within the tubes.

Either before or after the arm is lowered 50 the grenade or other object to be thrown, is placed in the cup k , the spring strips k^5 preventing its falling out of the cup when the cup is in the position shown in Fig. 2.

All being ready for throwing, the hook a^5 55 is tripped (raised) by means of the handle a^6 , thereby releasing the throwing arm, which, under the force of the pull exercised upon it by the chain f^5 due to the pressure of the air in the tubes, is rapidly flung upward, about its axis, until it reaches the position shown in Fig. 4, when it is suddenly 60 pulled up or stopped, and thereby caused to discharge the grenade out of the cup k in the required direction, and, under the energy developed by the arm, for the required distance. The sudden pulling up or stopping

of the arm is brought about by the quadrant h reaching a position where it begins to exert, through the chain f^5 , a downward pull on the cross-bar f^1 against the upward pressure of the air in the tubes. In 70 this way the air is used both for operating the throwing arm and for arresting its movement, and in the latter connection it also acts as a shock absorber.

For throwing the next grenade, the throwing arm is again lowered and again re-latched by the hook a^5 , whereupon the air in the tubes is automatically restored to its original pressure. With a grenade then placed in the cup, the hook a^5 is again 80 tripped, when the arm is again flung upward by the pressure of the air, until the point of delivery is reached (Fig. 4), when the grenade leaves the cup as previously described.

By repeatedly lowering the throwing arm, placing each time a fresh grenade in the cup, and releasing the hook a^5 , a succession of grenades may be rapidly discharged.

As only the expansion of the air in the tubes is used for operating the plungers, there is no necessity to pump more air into the tubes after each operation of the throwing arm, but, on the contrary, a practically constant or standing head of pressure is al- 95 ways available.

By varying the angular position of the cup k relatively to the throwing arm, the trajectory of the grenade may be varied. That is to say, the farther the cup is moved 100 in one direction about its pivot k^2 the greater the elevation of the trajectory, while the farther the cup is moved in the opposite direction about its pivot the flatter the trajectory. Very slight angular adjustments of the cup 105 have been found to give a considerable variation in the trajectory.

By moving either end of the base c side-wise, the direction of throw may be readily varied, and with the whole machine lightly 110 constructed, this is an easy operation. To guard against the accidental disturbance of the machine while throwing a grenade, the base c may have battens c^1 , c^2 see Fig. 3, 115 lying below the base and projecting beyond the sides of the base, and upon these battens sand bags may be placed. When the machine is not in use, the battens may be swiveled below the base, and thus lie out of the way, as well as allow of the machine 120 being neatly packed, see Fig. 5.

By providing the base with the raised bifurcated part and hinging the tubes thereto, the machine can be folded up, see Fig. 5, without requiring to detach the throwing arm. Further, the cup and its parts are 125 protected from injury while in transit.

Referring now to Figs. 10 and 10¹, a tubular metal (or solid wood) post l is used which is, by preference, detachably secured to the 130

base *c*. To such post is braced the three tubes a^1 , a^2 , a^3 collectively forming the air chamber. Within the tubes a^1 , a^3 are plungers *f*, *f* and at their upper end the plungers are 5 joined by a cross-pin carrying an anti-friction roller *m*. At the top of the post *l*, and extending forwardly therefrom, is a forked bracket *l*¹, and fulcrumed upon a fixed axis carried by the bracket is the throwing arm 10 *g*. This throwing arm overlies the roller *m* carried by the plunger cross-pin. To the free end of the arm *g* is applied the grenade holder *k*. Connected at one end to the arm *g* and at the other end to the base *c* is a stout 15 cord *o*.

In using this construction of the throwing machine, air is first pumped into the tubes a^1 , a^2 , a^3 to the required pressure, the arm *g* being preferably held down during the 20 pumping operation by the double hook *p* engaging a pin *p*¹ on each side of the arm. A grenade being then placed in the holder and all being ready to throw the grenade, the hook *p* is tripped, and the arm *g* made 25 free, whereupon the arm, under the pressure of the air in the tubes acting upon the plungers, is flung upward about its axis until it reaches the position shown by the dotted lines, when it is suddenly stopped by the 30 cord *o*, which is then fully distended. With such sudden arresting of the movement of the arm the grenade is discharged from the cup at a high speed in the desired direction and for the desired distance.

35 To help to maintain a uniform angular acceleration of the throwing arm during the rise of the plunger, the throwing arm is formed or provided with a shaped part *g*^{*} for the plungers to act against.

40 Owing to the limited arc of movement of the throwing arm in this form of the machine a high pressure of air is required to obtain the desired velocity of the arm for throwing, and as it appears to be the fact, that, the 45 greater the arc of movement, the greater the momentum of the throwing arm, it is preferred to employ the construction of machine shown in Figs. 1 to 9.

50 As will be seen from the foregoing description the machine shown either in Figs. 1 to 9, or Fig. 10 of the drawings is comparatively simple in construction, and, owing to the base and throwing arm being of wood, and the metal parts being tubular 55 or of thin section, the machine as a whole is comparatively light and portable. And either when in use (Fig. 2), or when folded up (Fig. 5), it can be readily carried about by one person. Further, when folded up it lies in small compass, and may, if desired, form part of the bomber's kit. A pair of straps *c*^{*} serves to hold the parts compactly together when folded.

60 Referring now to Fig. 13 and to the means 65 for "firing" the grenade prior to throwing

the bottom of the cup *k* is provided with a boss or bush *q* through which slidably projects a piercer *q*¹. Engaging this piercer at its rear end is one arm of a small bell-crank lever *r*, fulcrumed say to the cup as shown. 70 To the other arm of such lever is connected one end of a Bowden wire *r*¹, the outer case or sheath of which lies alongside and is secured to the throwing arm. The other end of the Bowden wire is adjustably connected 75 to a lever arm *r*² pivoted to the quadrant *h*. Under the weight of the free end of the lever, a slight pull is exerted on the wire, which serves to hold the piercer *q*¹ normally retracted and with its point within the said 80 bush *q*. Upon one of the brackets *d* is a stop pin *s*, which, as shown, lies in the path of the free end of the lever arm *r*².

With the grenade to be thrown provided 85 with a percussion cap, time fuse and detonator, and with the grenade placed in the cup *k*, the percussion cap lies directly opposite the point of the piercer. While the throwing arm is moving upward about its axis, but just before the grenade is due to leave 90 the cup, the piercer *q*¹ is caused to move rapidly forward and pierce the cap. This is brought about by the free end of the lever arm *r*² meeting the stop pin *s*, which, by offering a resistance to the further bodily 95 movement of the lever, causes the lever, with the further movements of the arm, to move about its own fulcrum and, through the Bowden wire, rapidly operate the piercer. In this way the machine is adapted to both 100 "fire" and throw the grenade. Upon the throwing arm being again lowered, the piercer is retracted, and remains retracted, while the next grenade is placed in the cup 105 and until the arm again reaches the firing point. In this way there is no danger of the grenades being pierced while placing them into the cup.

In Fig. 14 the apparatus is shown as 110 adapted for "firing" and throwing a grenade of the kind which is usually fired by means of what is termed a "striker." Instead, however, of the striker being part of the 115 grenade as heretofore, it is made part of the throwing machine. In the example shown in Fig. 14, *t* is the striker, the stem of which passes slidably through the bush *q* in the floor of the cup *k* and is connected, as in the case of the piercer in Fig. 13, with devices, such as the lever *r*, the Bowden wire *r*¹ and 120 the lever arm *r*² whereby, on the throwing arm being moved upward to throw the grenade, the lever *r* will serve to sharply operate the striker, just prior to the grenade leaving the cup, to force it against the percussion cap of the grenade and thus "fire" the grenade. Upon the arm being lowered the 125 striker will be moved back, ready for the next firing operation.

130 The moment or point at which the piercer

or striker shall be operated to fire the grenade during the upward movement of the throwing arm may be varied by adjusting the position of the stop pin *s*.

5 In transferring the piercer or striker from the grenade to the machine, and operating it by the machine, the dangers attending the handling and throwing of grenades are considerably reduced. Moreover, the grenade 10 itself is rendered safer to handle prior to throwing.

Means similar to that used for operating the piercer or striker may be employed for operating grenade-releasing devices upon

15 the cup. An example of one arrangement is shown in Fig. 15, *k*⁷ being a spring blade secured to the cup and bent inwardly toward the grenade, while *k*⁸ is a slide adapted to be pushed forward by hand and to hold the 20 bent end of the blade *k*⁷ against the grenade, and also adapted to be pulled back and allow the blade to move clear of the grenade. Such pulling back is effected by a wire and lever operating automatically with the movement of the throwing arm, the arrangement of the wire and lever being identical with that of the wire and lever shown in Fig. 13.

While intended chiefly for use in throwing grenades, or throwing and "firing" grenades, 30 it will be understood that the improved machine may be used for other throwing purposes, and in such connection may be used for games of skill, or for sport, and, if made on a small scale, it may be used as a toy.

35 What I claim is:—

1. In apparatus for throwing grenades and the like, and for like throwing purposes, a relatively fixed air chamber, movable air-compressing means within the chamber, a 40 non-return air inlet valve for allowing air to be stored in said air chamber under pressure, a throwing arm axially supported upon said chamber, grenade or like holding and controlling means on said throwing 45 arm, means for holding the arm retracted against the resistance of the air in the air chamber, and means for releasing the arm, the movable air-compressing means, under the pressure of the air within the air chamber, acting upon the throwing arm, and, on the 50 arm being released, operating the arm to throw the grenade, or other object, as set forth.

2. In apparatus for throwing grenades 55 and the like, and for like throwing purposes, a relatively fixed and tubular air chamber, plungers within the air chamber, and means for connecting the plungers to each other at the upper end, means for allowing air to be stored under pressure in the air chamber and a throwing arm axially supported near to the upper end of the air chamber, a quadrant upon the same axial support as the throwing arm and adjustably connected to 60 the arm, a chain connected to one point in

the curved edge of the quadrant, a chain wheel and axial support therefor on the air chamber, and said chain, after passing below said wheel, being connected to the plunger-connecting means, means for temporarily holding the throwing arm and plungers retracted against the pressure of the air in the air chamber, and means for releasing the arm for throwing, said chain transmitting the motion of the plungers to 70 the quadrant, and, on the plungers reaching the end of their outward stroke, serving to suddenly arrest the movements of the throwing arm, as set forth.

3. In apparatus for throwing grenades 80 and the like, and for like throwing purposes, an air chamber, a relatively fixed supporting base to which the air chamber at its lower end is hingedly connected, means for staying the upper end of the air chamber to 85 the base, air compressing means slidably fitting the air chamber, means for enabling air to be stored under pressure in the air chamber, a throwing arm, brackets and a fixed axis therefor near the upper end of the 90 air chamber, and means between the said air-compressing means and the throwing arm adapted, under the pressure of the air, to operate the throwing arm, and also to suddenly arrest the movement of the arm 95 when it reaches its highest velocity, grenade or like holding and controlling means on the throwing arm, means for temporarily retaining the arm and air-compressing means retracted against the resistance of 100 the air in the air chamber and means for releasing the throwing arm when requiring to throw the grenade or other object, as set forth.

4. In apparatus for throwing grenades 105 and the like, and for like throwing purposes, a series of tubes arranged side by side, means for supporting the same in a substantially vertical position, a plunger in two of the tubes and a cross-head for connecting such 110 plungers together at the upper end, a non-return inlet valve for allowing air to be stored in the tubes under pressure, a throwing arm, brackets and an axis therefor near the upper end of said tubes, and means 115 whereby the movement of the plungers in one direction may be communicated to the throwing arm, and vice versa, as set forth.

5. In apparatus for throwing grenades 120 and the like, and for like throwing purposes, a relatively fixed tubular air chamber, means whereby a standing body of air is maintained under pressure within the air chamber, a throwing arm axially mounted on the air chamber, and means for transmitting 125 the expansion of the air in the air chamber to the throwing arm, as set forth.

6. In apparatus for throwing grenades 130 and the like, and for like throwing purposes, a relatively fixed air chamber, air-compress-

ing means within the said chamber, an air inlet valve for allowing air to be stored in said air chamber under pressure, a throwing arm axially mounted on said air chamber, means for transmitting the motion of the said air-compressing means to the throwing arm, a cup-like grenade holder on said arm, and means whereby the grenade is temporarily held in the holder but is free to leave the holder on the throwing arm reaching the limit of its throwing movement, as set forth.

7. In apparatus for throwing grenades and the like, and for like throwing purposes, a relatively fixed air chamber, air compressing means within the said chamber, an air inlet valve for allowing air to be stored in said air chamber under pressure, a throwing arm axially mounted on said air chamber, means for transmitting the motion of the said air-compressing means to the throwing arm, a cup-like holder on said arm, means for retaining the object to be thrown in the holder, and means on the throwing arm for automatically releasing the said object when the arm reaches its highest velocity, as set forth.

8. In apparatus for throwing grenades, a relatively fixed air chamber, air-compressing means within the said chamber, an air-inlet valve for allowing air to be stored in said air chamber under pressure, a throwing arm axially mounted on said air chamber, and means for transmitting the motion of the said air-compressing means to the throwing arm, a cup-like grenade holder on said arm, means for retaining the grenade in the holder, means on the throwing arm for automatically "firing" the grenade in the holder, and means for automatically releas-

ing the grenade when the arm has reached its highest velocity, as set forth.

9. In apparatus for throwing grenades and the like, a tubular air chamber, with non-return air inlet valve, plungers within the air chamber, a throwing arm axially supported upon the air chamber and grenade carrying and retaining means on the throwing arm, the plungers being adapted to operate upon the throwing arm under the expansion of air in the reservoir, and said grenade-carrying and retaining means consisting of a cup having springs within it whereby the grenade is held yieldingly in the cup until it requires to leave the cup in the act of being thrown, as set forth.

10. In apparatus for throwing grenades and the like, and for like throwing purposes, a relatively fixed air chamber, air-compressing means within the said chamber, an air inlet valve for allowing air to be stored into said air chamber under pressure, a throwing arm axially mounted on said air chamber, and means for transmitting the motion of the said air-compressing means to the throwing arm, a cup-like grenade holder angularly adjustable upon said arm, means for holding same in various positions relatively to the arm, and means whereby the grenade is temporarily held in the holder but is free to leave the holder on the throwing arm reaching the limit of its throwing movement, as set forth.

In witness whereof, I have hereunto set my hand in the presence of two witnesses.

ABRAHAM WOOD.
